UNITED STATES PATENT OFFICE.

JOHN BARTHOLOMEW MASERANG, OF BELLEVILLE, ILLINOIS.

HATPIN ATTACHMENT.

1,341,858.

Specification of Letters Patent.

Patented June 1, 1920.

Application filed October 16, 1919. Serial No. 330,951.

To all whom it may concern:

Be it known that I, JOHN B. MASERANG, a citizen of the United States, residing at Belleville, in the county of Saint Clair, State 5 of Illinois, have invented certain new and useful Improvements in Hatpin Attachments; and I do hereby declare the following to be a full, clear, and exact description of the invention, such as will enable others 10 skilled in the art to which it appertains to make and use the same.

This invention relates to pin fasteners, and more especially to the sliding guards therefor; and the object of the same is to 15 produce an attachment for hats and hat pins whereby the latter will be held in place with the point protected, and the band of the attachment will constitute an ornament for the hat.

20 Specifically the invention covers novel means for connecting the ends of the pin with the ends of the band, through the use of metallic terminals which are both ornamental and serviceable. Details are set forth 25 below and shown in the drawings wherein:

Figure 1 is a perspective view of a hat with this attachment applied.

Fig. 2 is an enlarged plan view of the pin and the metal parts at both ends thereof, the 30 band being indicated in dotted lines.

Fig. 3 is a still further enlarged sectional detail through the guard for the tip of the pin, and a perspective detail of the terminal for this end of the band.

35 Fig. 4 is a plan view of the terminal for the other end of the band before it is bent.

In Fig. 1 is shown a ladies' hat through which is passed a pin P having a sharp point S at one end and a head H fast on the 40 other. These pins are usually inserted through the crown of a hat and the hair, leaving the point projecting dangerously if it be not guarded. Broadly speaking, I propose to apply a guard to said point and draw 45 the guard onto the point by an elastic band B which connects this guard with the head. Said band may be of almost any variety of ornamentation according to the wearer's fancy, but in all probability it will be a piece 50 of elastic webbing to which is stitched a fulled or shirred ornamental facing so that the latter may expand as the former stretches. It is quite possible for the wearer to have several such ornamental bands for 55 use interchangeably with the hat pin.

Attached to or forming part of the head

H is a hook 1 preferably of rather stiff wire with its bill curved toward its shank so that it may be pressed into contact therewith to close the hook into an eye if desired. Engageable with this bill is a metal terminal best seen in Fig. 4. This is stamped from a single sheet of pliable material in the form of two leaves 2 and 3 having about four perforations 4 through them as shown, and a reduced neck 5 connecting the leaves and having through it a pair of eyes 6 as shown, and when the metal plate is folded on a transverse line between said eyes they come into register and may be engaged with the hook 1 while the leaves come against opposite sides of one end of the band B and are attached thereto by rivets or stitches passing through the registering perforations and the interposed band.

75 The guard best seen in detail in Fig. 3 comprises a tubular body closed at one end by an enlarged head or button 10, flared at its other open end to produce a mouth 11, and reduced between said ends to constitute a neck 12. Inclosing the neck are two U-bolts or clips 13. The terminal for this end of the band consists of a metal strip bent transversely at its midlength into a narrow leaf 14 and a wide leaf 15, both pierced with 80 perforations 16 adapted to register, and the other end of the band B is inserted between these leaves as will be clear. The clips are passed around the neck of the guard, and rivets 17 are passed through the clips and 85 perforations in the terminal and through the band which intervenes between its leaves. In a normal or contracted condition the 90 band should be shorter than the pin P.

95 When the eye of the upper terminal is engaged with a hook and the latter closed, the lower terminal carrying the guard hangs free. The pin can then be passed through the hat and the hair as usual, its point protruding beyond the hat crown as well known. 100 The band is now stretched and passed over the crown or around the side of it as seen in Fig. 1, and the guard is slipped over the tip or points of the pin, being drawn onto the same and strained against one side of it by the band which is deflected out of a straight line by reason of its passage around the crown. Thus the elastic band holds the guard on the pin, and the guard prevents the pin from becoming lost. Also the other 105 end of the band draws on the head of the pin, and especially if the latter is passed

through the hat crown at one side of the head rather than diametrically through the hat, the tension of the band will be exerted to hold both ends of the pin and prevent its accidental displacement.

What is claimed is:

A hat pin attachment comprising an elastic band adapted to be connected at one end to the head of the pin, a tubular guard 10 adapted to be slipped over the point of the pin, clips embracing the body of the guard, a terminal for the other end of the band con-

sisting of a metal plate folded across its mid-length to form leaves lying against opposite sides of the band, and rivets engaging 15 the clips and passing through both leaves of the terminal and the interposed band and holding the latter alongside said guard.

In testimony whereof, I affix my signature, in the presence of two witnesses.

JOHN BARTHOLOMEW MASERANG.
